UNITED STATES PATENT OFFICE.

AUGUSTUS C. WOOLMAN, OF BELLEFONTAINE, OHIO.

DESIGN FOR A HIP-STRAP BUCKLE.

SPECIFICATION forming part of Design No. 32,897, dated July 3, 1900.

Application filed June 9, 1900. Serial No. 19,782. Term of patent 7 years.

To all whom it may concern:

Be it known that I, AUGUSTUS C. WOOLMAN, a citizen of the United States, residing at Bellefontaine, in the county of Logan, State of Ohio, have invented and produced a certain new and original Design for a Hip-Strap Buckle, of which the following is a specification, reference being had therein to the accompanying drawings, in which—

Figure 1 is a perspective of a hip-strap buckle, and Fig. 2 is a longitudinal section through the same.

As shown in the drawings, the leading or material feature of the design consists of the slightly-curved hook portion A, having opposite inwardly-tapering sides A' and a curved angularly-disposed shank A², together with the substantially-rectangular buckle-

plate B, extending in a plane parallel with the hook portion and provided with rectangular openings B'. These openings are provided with beveled edges B², and one face of the hook has thereon the representation of a leaf, as shown at C in Fig. 1.

Having described my invention, what I claim as new, and desire to secure by Letters Patent, is—

The design for a hip-strap buckle substantially as herein shown and described.

In testimony whereof I affix my signature in presence of two witnesses.

AUGUSTUS C. WOOLMAN.

Witnesses:

JOHN KERNAN,
WILLIS POLLEY.
